No. 731,066.

PATENTED JUNE 16, 1903.

A. F. NYE,
MOLDING KNIFE PROTRACTOR.

APPLICATION FILED JUNE 9, 1902.

NO MODEL.

UNITED STATES PATENT OFFICE.

ALVIN F. NYE, OF ROCHESTER, NEW YORK, ASSIGNOR TO WALES M. NYE.

MOLDING-KNIFE PROTRACTOR.

SPECIFICATION forming part of Letters Patent No. 731,066, dated June 16, 1903.

Application filed June 9, 1902. Serial No. 110,866. (No model.)

To all whom it may concern:

Be it known that I, ALVIN F. NYE, a citizen of the United States, and a resident of Rochester, in the county of Monroe and State of New York, have invented certain new and useful Improvements in Molding-Knife Protractors, of which the following is a specification.

This invention relates to a molding-knife protractor for determining the proper contour of the knives used on machines for cutting moldings and like articles whereby with a pattern of any cross-section the pantograph automatically gives the contour of the knife-edge with which such pattern can be cut. Heretofore the edges of molding-knives have been determined by a laborious cut-and-try method and are not truly accurate. By this machine, however, the form of the knife-edge is accurately determinable.

In the drawings, Figure 1 is a top plan view of the device. Fig. 2 is a side elevation. Fig. 3 is an enlarged cross-section on the line 3-3 of Fig. 1. Fig. 4 is an enlarged view of one end of the members of the pantograph, and Fig. 5 is a cross-section of the head of a molding-machine having a knife attached thereto and showing its relation to a molding in process of being cut.

As shown by Fig. 5, the heads A of molding-machines are squared and are provided with means, such as T-slots α , whereby the knives may be attached to them. The shaft A' passes through the axis of the head. The knife B is attached to one of the flat sides of the square head by means of a bolt b in a manner well known. The heads A are from three to four inches square. The knife B, being fastened on one of the flat sides of the head, is always at an angle of the surface of the formed molding in order that its cutting edge should operate properly upon the wood and should have proper clearance, and said knife extends more or less beyond the corner of the head, so as to give chip-clearance to the extent of the needed depth to be cut into the blank from which the molding is formed. The vertical dotted line in Fig. 5, running from the arc of the circle that indicates the swing of the head and knife, represents the extreme depth of cut of the knife B, and it will be seen that the knife when cutting the upper edge α of the molding had already finished its cut on

the lower edge α' thereof. In other words, that portion of the knife which cuts deepest into the blank performs its cutting first, and that portion of the knife which cuts the least from the blank performs its cutting last. The dotted lines running from the lowest part of the edge of the knife in Fig. 5 to the center of the shaft shows by its angle with the first-mentioned dotted line the difference of position of the extreme cutting edges of the knife and shows that the contour of the knife-edge must differ by just so much from the right-angled cross-section of the molding. In Fig. 1 the full lines in the upper right-hand corner represent the form of the knife-edge, and the adjacent dotted lines represent the cross-sections of the molding and show the difference between the molding contour and the contour of the knife-edge. These lines differ from each other, as shown in Fig. 1, the line representing the knife-edge having more curvature than the dotted lines representing the molding.

The pantograph, proportioned for use with heads of three to four inches square, is made as follows: On a suitable base C a rod D of any suitable length is fastened by supports d . On this rod slides a sleeve E, which sleeve may move longitudinally along the rod and may also rock. This rocking is most easily provided for by making the rod D cylindrical; but the rod D may have any non-cylindrical contour fitting the sleeve E, provided in this case. The rod may rock in its bearings d . To the sleeve E is rigidly fastened the transverse base-arm F. To this base-arm are pivoted three bars. At one end is the pantograph-bar G, pivoted at g' , on the end of which is carried a marking-point g . The distance from the axis of the shaft D to the pivot-point g' of the arm G on the arm F is two inches. From the axis of the bar D to the pivotal point h' of the arm H on the arm F is three and five-sixteenths inches. On the same side as the arm H there is pivoted the arm J at a distance of one and three-fourths inches from the axis of the bar D. The arms J and H are pivoted to the arm F on a line at right angles to the bar D and eleven-sixteenths of an inch to the right on the parallel line passing through the pivotal point g' . The arms G, J, and H are connected by an arm

K, pivoted to each thereof at the points k , j , and h , so that said arm K is at right angles to the line of the bar D when in the position of the arm J shown in the drawings. The marking-point g is one and twenty-three thirty-seconds inches from the pivot k . The bar H, however, is pivoted to said bar K at a point h , which is four and one-fourth inches from the pivot k , while the pivot h' is five and five-sixteenths inches from the axis of the bar G. The arms G, F, H, and K constitute a quadrilateral polygon with unequal sides, one of which sides (the bar F) is moved in a straight line on the bar D. The tilting of the bar F is only a matter of convenience and is not functional. The end of the bar J carries a tracing-point J' at a distance of three-eighths of an inch from the pivotal center j . The pivots g' , j' , h' , h , and k are permanent.

The pivotal points g' and h' are five and eleven thirty-seconds inches apart, the points h' and h are four and one-half inches apart, the points h and k are four and one-fourth inches apart, the points g' and k are five inches apart, and the distance from g' to j' is three and three-fourths inches, while the distance from k to j' is variable from three and nineteen thirty-seconds to four inches for a purpose now to be explained.

For a head four inches square I provide a slightly-curved slot j^2 (having a line-of-beauty curvature) in the center of the arm J, through which the thumb-screw pivot-pin j may pass. The arm J for better bearing rests, as shown in Fig. 3, between two plates, one of which is the arm K and the other of which is a plate K' beneath said arm K and rigidly fastened thereto, so that said arm J extends between said two plates, and the pivot-pin j passes through a perforation in the arm K, through the slot j^3 , and being screw-threaded on its lower end engages similar screw-threads in said lower plate K'. If said pin j passes through the slot j^2 and the tracing-point J' is swung laterally, (up and down in Fig. 1,) the pin j will slide along the slot j^2 . The similar slots j^3 and j^4 (one on each side of the slot j^2) in the form of device shown are provided for drafting the edges of knives for attachment to heads of other sizes, because it will be seen that if the pin j is placed in the slot j^3 and the tracing-point is placed at a certain position the marking-point g will be farther from any base-line parallel to the line of the bar D, and therefore will produce a wider knife, while if the pin j is in the slot j^4 the back edge of the knife will be nearer to the cutting edge, and the knife drafted will be suitable for still another head.

On the bar k may be a caster L for facilitating the movement of the mechanism.

Upon the bed C of the machine are means for fastening thereon a knife-contour plate X. For this purpose I prefer two stops M M' and a clamping device N, which may consist of a spring that is adapted to be fastened to the base C by means of a screw n and can be

adjusted for pressing the plate X between the spring N and the stops M M'. The plate X may be of paper or wood or may be a metal plate, such as zinc, and the marking-point g may be of steel, so as to mark the contour of the knife edge with accuracy. Upon the base C also are suitable devices for clamping the pattern thereto, such as the flexible strips O O, fastened to said board at one end by the screws o and at the other end by the thumb-screw o', so that the paper pattern Y may be clamped to the base C, as shown in Fig. 1.

It is customary to set the knife to register with the edge of one of the faces of the head A, and in order to adapt this pantograph to this custom I set one of the stops M in such a position that the end of the knife-contour plate X shall register with the outer edge of 80 said stop M, as shown at the right hand of Fig. 1. On the base C is marked a corresponding line indicated by the arrow, (at right angles to the base,) which is as far distant from the corresponding line passing 85 through said edge of the stop M as the tracing-point J' in the position shown in the drawings is from a line passing through the marking-point g at right angles to the bar D. The pattern Y is so adjusted with reference to 90 this line indicated by the arrow that the corresponding side edge of the molding-pattern shall have the right distance from said line to permit the knife-pattern drawn therefrom to have the proper adjustment just described 95 with reference to the end of the head A.

It will now be seen that from the construction described the pantograph-frame may be moved sidewise or in line with the guide-bar D without relative change of the tracing-point J' and the marking-point g , but that lateral movements transverse to the line of the guide-bar D will cause slight changes of the marking-point g with reference to the tracing-point J' , and that as the tracing-point J' approaches the base-line Z marked on the board C the marking-point g will proportionately increase its travel over the travel of the tracing-point J' , so that the line marked by it will be nearer to the base-line, and as the pantograph is swung in the opposite direction and the tracing-point J' follows the contour on the molding-pattern Y the knife-edge drafted by the marking-point g will as it moves farther from the base-line Z increase the distance from 100 said base in proportion to the motion of the tracing-point J' . This increase and decrease is due to two facts—the different lengths and the lack of parallelism of the arms G and H and the fact that the arm J is maintained 105 nearly but not quite parallel with the arm G, the variation in parallelism being controlled by the contour of the slots j^2 , &c., on each side of a line in or parallel to a line joining the pivotal centers j' and j .

The device may be enlarged or reduced in substantially the proportions stated, and the increase or decrease of movement of the point g with reference to the point J' may be varied

by changing the angularity of the slots ², &c., with reference to the line of the bar G.

What I claim is—

1. In a pantograph for substantially the purposes described, the combination of a quadrilateral frame pivoted at its corners, having one member supported on a straight-line-guiding device, in combination with a bar pivoted to said member by a fixed pivot and to the opposite member by a slot-and-pin connection.

2. In a pantograph for substantially the purposes described, a straight-line-guiding device, a member supported thereon and transversely thereto, two bars of unequal lengths pivoted on said member and extending in the same direction therefrom, a bar pivotally connected to said two bars and thereby forming a quadrilateral figure having unequal sides and a fifth bar pivoted to said first-mentioned member and having a slot-and-pin connection to the last-mentioned bar.

3. In a pantograph for substantially the purposes described, the combination of a quadrilateral frame pivoted at its corners, having one member supported on a straight-line-guiding device, in combination with a bar pivoted to said member by a fixed pivot and to the opposite member by a slot-and-pin connection having a tracing-point on its outer end and a marking-point on the outer end of a member of said frame parallel, in one position, to said bar.

4. In a pantograph for substantially the purposes described, a straight-line-guiding device, a member supported thereon and transversely thereto, two bars of unequal lengths pivoted on said member and extending in the same direction therefrom, a bar pivotally connected to said two bars and thereby forming a quadrilateral figure having unequal sides and a fifth bar pivoted to said first-mentioned member and having a slot-and-pin connection to the last-mentioned bar and having a tracing-point on its outer end, and a marking-point on the outer end of the longer of said two first-mentioned bars.

5. In a pantograph for substantially the purposes described, the combination of a quadrilateral frame pivoted at its corners, having one member supported on a straight-line-guiding device, in combination with a bar pivoted to said member by a fixed pivot

and to the opposite member by a slot-and-pin connection, a base, a clamping device on said base for the pattern and a clamping device for the copy embodying guiding means therefor. 55

6. In a pantograph for substantially the purposes described, a straight-line-guiding device, a member supported thereon and transversely thereto, two bars of unequal lengths pivoted on said member and extending in the same direction therefrom, a bar pivotally connected to said two bars and thereby forming a quadrilateral figure having unequal sides 65 and a fifth bar pivoted to said first-mentioned member and having a slot-and-pin connection to the last-mentioned bar, a base, a clamping device on said base for the pattern, and a clamping device for the copy embodying guiding means therefor. 70

7. In a pantograph for substantially the purposes described, the combination of a quadrilateral frame pivoted at its corners, having one member supported on a straight-line-guiding device, in combination with a bar pivoted to said member by a fixed pivot and to the opposite member by a slot-and-pin connection having a tracing-point on its outer end and a marking-point on the outer end of 80 a member of said frame parallel, in one position, to said bar, a base, a clamping device on said base for the pattern and a clamping device for the copy embodying guiding means therefor. 75

8. In a pantograph for substantially the purposes described, a straight-line-guiding device, a member supported thereon and transversely thereto, two bars of unequal lengths pivoted on said member and extending in 90 the same direction therefrom, a bar pivotally connected to said two bars and thereby forming a quadrilateral figure having unequal sides and a fifth bar pivoted to said first-mentioned member and having a slot-and-pin connection to the last-mentioned bar and having a tracing-point on its outer end, and a marking-point on the outer end of the longer of said two first-mentioned bars, a base, a clamping device on said base for the pattern, 95 and a clamping device for the copy embodying guiding means therefor. 100
